UNITED STATES PATENT OFFICE.

JOHN F. KNAPP, OF OMAHA, NEBRASKA.

CAR-STEP.

SPECIFICATION forming part of Letters Patent No. 365,924, dated July 5, 1887.

Application filed October 18, 1886. Serial No. 216,471. (No model.)

To all whom it may concern:

Be it known that I, JOHN F. KNAPP, a citizen of the United States, residing at Omaha, in the county of Douglas and State of Nebraska, have invented certain new and useful Improvements in Steps for Railroad Coaches; and I do declare the following to be a full, clear, and exact description of the invention, such as will enable others skilled in the art to 5 to which it appertains to make and use the same, reference being had to the accompanying drawings, and to the letters and figures of reference marked thereon, which form a part of this specification.

15 This invention relates to extension-steps for vehicles, principally designed for railroad-cars.

The improvement consists in the means for supporting the movable step and the devices for raising and lowering the same, which will 20 be more fully hereinafter set forth, claimed, and shown in the annexed drawings, in which—

Figure 1 is a rear perspective view of a pair of steps provided with my improvements, and 25 Fig. 2 is a front perspective view thereof.

The object of the improvement is the construction of a pair of steps which can be readily lengthened and shortened, easily operated from the ground or platform, and which will 30 at the same time be simple in arrangement, efficient and durable in use, and not liable to get out of repair. Such steps are principally designed for vehicles and railroad-coaches and sleeping-cars, so that the passengers may the 35 more easily enter and leave such vehicles without the inconvenience usually experienced by reason of the long step commonly found between the ground and the bottom step. The steps shown may be of any well-known and 40 approved construction, and comprise the sides A and A', the risers B, and the steps C. The steps are provided near each end with the plates D, which are secured at their inner portions to the steps, and have transversely-apertured lugs d extending from their rear edge.

45 The rods E pass through the openings in the lugs d, and are guided in their movements thereby. A portion near their upper ends is provided with teeth e, which are adapted to 50 mesh with pinions f, keyed on the shaft F, journaled between the sides A and A'. The

gear-wheel F', secured to the shaft F near one end, is engaged by the hand rack-bar G, held and guided in its movements by keepers g, secured to the side A. The hand rack-bar 55 projects through the platform H and terminates in the loop g'. The notch g' in its side is engaged by the stop h, which holds said hand rack-bar in its highest position. The step I is secured to the lower ends of the 60 toothed bars E and are carried thereby.

In practice, when it is desired to shorten or lengthen the steps, the stop is disconnected from the hand rack-bar and the same pushed down, (or if hand rack-bar be placed on opposite side of gear-wheel F, pulled up,) when the shaft F will be rotated and the bars E moved down or upward and carry the step with them. The shaft may be extended at one 65 end and pass through one of the sides, and be provided with or adapted to receive the crank J, (also gear-wheel F, if it be desired to place it upon the outside,) by which it can be operated independent of the hand rack-bar. It will be understood that the gear-wheel and 70 hand rack-bar may be arranged outside of the step, the rack-bar in this instance being extended alongside of the front sill of the platform and held by suitable guides.

I am aware that steps for vehicles have been 75 lengthened and shortened by a movable step, which step is carried by rack-bars working in guides secured to the sides of the steps, said rack-bars having motion imparted thereto from a shaft journaled transversely of the 80 steps and having pinions keyed thereon near each end meshing with the rack-bars. A handle secured to the shaft serves to actuate the same when it is desired to lengthen or shorten the steps.

Having thus described my invention, what 85 I claim, and desire to secure by Letters Patent, is—

1. The combination, with the steps, the plates secured at their inner ends near each 90 end of the steps proper, and having their outer ends transversely apertured, the toothed bars passed through the apertured ends of said plates and guided in their movements thereby, the steps secured to the lower ends of the bars, 95 the shaft journaled transversely of the steps, the pinions keyed upon the shaft and mesh-

ing with the teeth of said toothed bars, of the gear-wheel secured upon the shaft, and the hand rack-bar held in engagement with the gear-wheel, whereby a longitudinal movement 5 of said rack-bar will effect a corresponding movement of the toothed bars and steps, substantially as and for the purpose described.

2. The combination of the steps, the toothed rods, the step secured to their ends, the shaft, to the pinions keyed thereto and meshing with

the teeth on said bars, the gear-wheel, the hand rack-bar held in engagement with the gear-wheel, the crank, and the stop, substantially as and for the purpose described.

In testimony whereof I affix my signature 15 in presence of two witnesses.

JOHN F. KNAPP.
